Attorney,

UNITED STATES PATENT OFFICE.

JEAN M. ALLEAS, OF BOSTON, MASSACHUSETTS.

AEROPLANE.

1,015,924.

Specification of Letters Patent.

Patented Jan. 30, 1912.

Application filed May 3, 1911. Serial No. 624,748.

To all whom it may concern:

Be it known that I, JEAN M. ALLEAS, a citizen of the United States, residing at Boston, in the county of Suffolk and State 5 of Massachusetts, have invented certain new and useful Improvements in Aeroplanes, of which the following is a specification.

This invention has reference to flying machines of the aeroplane type, and it is the 10 object of the invention to provide in a machine of this kind a novel arrangement of sustaining planes, and means for adjusting the same to maintain the machine in equilibrium.

15 The invention also has for its object to provide for an adjustment of the planes whereby they may be made to serve as a parachute to check the descent of the machine in case of accident.

20 In order that the invention may be better understood, reference is had to the accompanying drawings forming a part of this specification, in which—

Figure 1 is a side elevation of the machine. Fig. 2 is a plan view thereof. Fig. 3 is a detail view showing the support of the front propeller. Fig. 4 is a similar view showing the support of the rear propeller. Fig. 5 is a plan view, partly in section, of 25 the parts shown in Fig. 3. Fig. 6 is a plan view of the steering mechanism. Fig. 7 is an elevation of the operating devices of the steering line. Fig. 8 is an elevation of the mechanism for tilting the front planes. Fig. 9 is a diagrammatic view showing the 30 main sustaining planes adjusted to form a parachute.

Referring specifically to the drawings, the frame of the machine comprises front and 35 rear uprights 10 and 11, respectively, suitably braced and mounted on wheels 12, and connected by longitudinal side bars 13 at the bottom. Midway between the front and rear ends of the machine is located a standard 40 14 which rises to a suitable height from a cross bar 15 carried by the side bars 13, and is suitably braced by guy wires. This standard and the uprights support a pair of spaced longitudinal beams 16, which later support the propellers to be presently 45 described.

The machine has two top transverse planes 17 and 18, respectively, the former being located at the front, and the latter at 50 the rear. Beneath the front plane are located two transverse planes 19 which ex-

tend outwardly from opposite sides of the machine. A similar pair of planes 20 is located beneath the rear plane. It will therefore be seen that the machine is provided 55 with six sustaining planes.

Beneath the planes 19 are located small transverse planes 21 which are provided for the purpose of maintaining the lateral stability of the machine, these planes being 60 pivoted at 22 to the front uprights 10, and one of said planes being located on each side of the machine. The rear ends of the planes are connected by links 23 to foot 65 pedals 24 so that they may be tilted to vary 70 the angle of incidence. If the machine tilts to one side, the plane 21 on the opposite side of the machine is adjusted to have a greater angle of incidence, whereupon the machine is righted. By providing these 75 stabilizing planes, it is not necessary to warp the main sustaining planes.

The two top planes 17 and 18 are pivotally connected intermediate their front and rear ends so that they may be tilted fore 80 and aft, and by providing two of these planes, they may be set so as to operate as a parachute to check the descent of the machine. This is done by tilting the front 85 end of the rear plane upwardly and the front end of the front plane downwardly, as shown in Fig. 9.

The top planes 17 and 18 are carried by ribs 25 extending fore and aft, and pivoted to a cross bar 26 carried by the uprights 19 and 11. The bottom planes 19 and 20 are mounted in a similar manner and they are connected to the top planes by rods 27.

The front lower planes 19 have a curved 95 rib 28 on which is mounted a segmental gear 29 meshing with a pinion 30 carried by a transverse shaft 31 supported in suitable bearings on the uprights 10. This gearing is employed for tilting the front planes, the upper and lower planes being tilted simultaneously by reason of the connection 100 27 therebetween.

Each lower plane 19 is provided with the herein-described gearing, and the shaft 105 31 operates both gears. This shaft carries a pulley 32 around which passes a cable 33 which extends downwardly and over a guide pulley 34, and thence upwardly to a drum 35 on which latter it is made fast and 110 wound. The drum is loosely mounted on a shaft 36 and is provided with a hand wheel

37. The shafts of the pulley 34 and the drum 35 are supported by standards 38 carried by the frame of the machine.

To the front and rear ends of one of the 5 ribs 39 of each bottom plane 20 is fastened the ends of a cable 40 which extends intermediate its ends around a pulley 41 mounted on a shaft 42 carried by the rear upright 11. This shaft is also provided with a pulley 43 around which passes a cable 44 which 10 extends forwardly to a guide pulley 45 loosely mounted on the same shaft as the guide pulley 34. From the pulley 45 the cable extends upwardly and is wound on a drum 46 which is loosely mounted on the same shaft as the drum 35 and has a hand wheel 47. It will be evident from the foregoing that when the drum 46 is rotated, the motion will be transmitted to the shaft 42 15 through the cable 44, whereupon the rear planes are tilted through the connection of the cable 40 therewith. The top rear plane is tilted simultaneously with the bottom plane by reason of the connections 27 there- 20 between. The angle of incidence of both sets of planes may therefore be adjusted to properly control the flight of the machine and in case of accident the planes may be set as shown in Fig. 9, in which position 25 they operate as a parachute and serve to check the descent of the machine.

At the rear end of the machine are mounted vertical rudders 48 for controlling the lateral direction thereof. Two of these 30 rudders are employed, they being carried by vertical shafts 49 supported by cross bars 50 mounted on the rear uprights 11. The rudders are connected at one of their ends by a rod 51, and to their other ends are connected the two ends of an operating cable 52 which cross and pass over a pulley 53 as shown in Fig. 6, and then extend forwardly and over a pulley 54 loosely mounted on the shaft of the pulleys 34 and 45, 35 from which pulley 54 the cable extends upwardly to and is wound around a drum 55 loosely mounted on the same shaft as the drums 35 and 46, said drum 55 also being provided with a hand wheel 56.

50 The machine is driven by two propellers 57 and 58, respectively, the former being located in front, and the latter in the rear. The propellers are right and left handed, respectively, and are driven in opposite directions. Separate driving means are provided, the same comprising motors 59 and 60, respectively, the former driving the front propeller and the latter the rear propeller. By providing a separate motor for each propeller, the machine can be kept under control in case of accident to one of the propellers or motors, and it would then not be necessary to descend by gliding. The motors are internal-combustion engines.

65 In order to facilitate the ascent of the

machine, the propellers are arranged so that they can be adjusted to extend at different angles to the horizontal, which adjustment is effected by the following means: The shaft 61 of the front propeller is supported in bearings 62 formed on one side of a disk 63. A cross-piece 64 connects the bearings, and said cross-piece is formed with a trunnion 65 which is journaled in one of the longitudinal beams 16. From the other side of the disk 63 extends a trunnion 66 which is in axial alinement with the trunnion 65 and is journaled in the other longitudinal beam 16. On the trunnion 65 is made fast a worm gear 67, and on said trunnion is also loosely mounted a beveled spur wheel 68. The propeller shaft 61 has a beveled pinion 69 which is in mesh with the spur wheel 68. The engine shaft 70 is connected by a universal joint 71 to a shaft 72 which carries a beveled pinion 73 meshing with the spur wheel 68. The worm gear 67 is in mesh with a worm 74 carried by a shaft 75 provided with a hand wheel 76. The motion of the shaft 72 is transmitted to the propeller shaft 61 through the gears 73, 68 and 69. The angular adjustment of the propellers is effected by operating the shaft 75, whereupon, through the worm gearing, the trunnion 66 is rotated, and as 90 said trunnion is carried by the disk 63, the bearings 62 of the propeller shaft are swung in a direction to change the angle of the propeller shaft with respect to the horizontal.

100 The shaft 77 of the rear propeller is mounted in substantially the same manner as the shaft of the front propeller, with the exception that the worm shaft is positioned and operated in a different manner. The 105 worm shaft 75 already described extends horizontally and has a hand wheel 76. The worm shaft 78 for adjusting the rear propeller is arranged vertically and has a sprocket wheel 79 which is connected by a 110 sprocket chain 80 to a sprocket wheel 81 on a vertical shaft 82 supported by the beams 16, and having its lower end fitted with a hand wheel 83. The beams 16 also carry seats 84 and 85, respectively, for operators, 115 the seat 84 being located adjacent to the hand wheel 76, and the seat 85 adjacent to the hand wheel 83. The several hand wheels which control the planes and the rudder are located adjacent to the seat 84. 120 The drive shaft 86 of the rear propeller is connected by a sprocket and chain gearing 87 to the shaft 88 of the rear motor 60.

I claim:

In an aeroplane, a supporting frame, pivoted front and rear sustaining planes at the top of said frame, pivoted bottom planes extending from opposite sides of the frame at the front and rear thereof and located beneath the top planes, said top and bottom 130

planes and their pivotal axes being transverse of the direction of flight, a connection between the top and bottom front planes and between the top and bottom rear planes, 5 means for independently tilting the front and rear planes, pivoted stabilizing planes extending from opposite sides of the frame beneath the front bottom planes, said stabilizing planes and their pivotal axes be-

ing transverse of the direction of flight, and 10 means for independently tilting the stabilizing planes.

In testimony whereof I affix my signature in presence of two witnesses.

JEAN M. ALLEAS.
